Hugo J. Buchanan-Wollaston
by Herbert H. Jenner, Attorney

UNITED STATES PATENT OFFICE.

HUGO JOHN BUCHANAN-WOLLASTON, OF LOWESTOFT, ENGLAND.

TIGHTENING AND GRIPPING DEVICE FOR STRING EMPLOYED IN THE TYING OF PARCELS.

Application filed June 11, 1926, Serial No. 115,209, and in Great Britain June 20, 1925.

This invention relates to improvements in tightening and gripping devices for string and whilst mainly intended for use in connection with string employed in the tying of parcels and the like and for securing one object to another, the invention in its larger form may be used as a tightening and gripping and holding device for cords or ropes of much larger diameter than that necessary for 5 the lighter work. It may also be used in connection with flat leather straps, webbing or the like for various purposes as for instance in securing parcels or articles to carriers on bicycles.

10 The main object of my invention is to avoid tying the string or rope into knots in using it for the purposes indicated, thus economizing in the amount of string used and enabling the whole of it to be employed again when required, since the forms of clip designed by me enable it to be readily removed from the clip after first use.

15 With the aforesaid object in view my invention relates to clip or grip devices of two types, one of which is used where definite lengths of string or cord are first cut off to length and the other both for string so cut off and for string formed in a ball, wound upon a bobbin or wound into the more modern 20 "cross-wound" cheese form, in which latter cases the required amount of string can be used and cut off after the tying is effected.

25 My invention consists in one form in a clip made from one piece of metal perforated and provided with one or a pair of resilient integral gripping tongues for the string; in another form in which the clip consists of a base element of closed or partly open form to which a separate gripping tongue, or tongues, 30 is fixed; in a further form in which the gripping tongue, or tongues is pivoted to the base and in some cases spring-controlled whilst in a further form the gripping tongue is movable about a vertical pin or the like supported 35 by the base.

40 My invention will be fully described with reference to the accompanying drawing, showing it in various forms and in which,

45 Fig. 1 is a plan of a clip made in one piece 50 of metal,

Figs. 2 and 3 plans of a two-piece clip, and Fig. 4 perspective view of a tube herein-after referred to,

Figs. 1 to 3 show a clip for use when the string or cord is previously cut to length 55 whilst the figures hereinafter referred to are used both when the string is cut off to length either before or after tying is completed. In the latter figures,

Fig. 5 is a plan of a one-piece clip,

60

Fig. 6 is a plan of two-piece clip,

Fig. 7 sectional end elevation of the clip shown in Fig. 6,

Fig. 8 plan of another two-piece clip,

Fig. 9 plan of a two-piece clip with the 65 parts separated,

Fig. 10 plan of clip in Fig. 9 with parts assembled,

Fig. 11 end elevation of Fig. 10,

Fig. 12 plan and Fig. 13 side elevation 70 respectively of a clip having gripping tongues pivoted to the base, and

Fig. 14 plan of a two-piece clip with single gripping tongue.

75 Referring to Fig. 1, the clip body *a* is made of sheet metal, preferably thin steel of suitable outer shape, slit at each end to provide two resilient tongues *b*, the latter being slightly shortened and serrated at their outer ends to form teeth *c*. The tongues are bent upwardly from their root ends *d* above the face of the body *a* and the sides of the latter are pressed inwardly to the position shown by broken lines *e*, to hold the tongues against the tensile stress set up in the string. Curved 80 spaces *f*—which for ordinary string should be very narrow—are left between the serrated ends of the tongues *b* and the ends of the body *a* through which the ends of the cut string are pulled from the underside. Thus in tying-up 85 a parcel or other object one end of the string is passed a little distance through one of the spaces *f* thus flexing the tongue. On tension being released the string is gripped between the teeth *c* and the inner edge *g* of the body *a*. 90 The other end of the string is taken round the parcel and passed through the other space *f*. By pulling on this end of the string and holding the other end the clip is used as a link until 95 the string is tight. On letting go, the second 100

tongue *b* grips the string and holds it in tension. Both ends of the string may be pulled in tightening it up if required.

Fig. 2 shows a two-part clip comprising a body *a* of perforated form and a two-tongue part *b* which is secured against the upper face of the body by clamping the lateral edges *h* tightly round the edges of the body. The clip acts in the manner previously described.

Fig. 3 shows another two part clip in which the body *a* is made from wire roughly in the form of a letter S, the central portion *i* of which passes through holes *j* in the double tongue part *b*, whilst the curved ends pass under the tongue as shown and lie tightly against it.

It is frequently and usually desirable to tie up a parcel with string uncut from a ball, bobbin or "cheese". With the forms of clip described this cannot be done. To accomplish this end the body *a* of the clip must be gapped at one or two points, to permit of the uncut portion of the string to be passed into one or other of the curved spaces *f* beneath the tongues *b*. One gap is enough but I prefer to use two. In Fig. 5 the arrangement is shown applied to the one piece clip indicated in Fig. 1, *h* being the gaps cut in the body at opposite sides and ends. In other respects the construction of the clip is the same as Fig. 1. In the case of Fig. 5, the end of the tying string may either be passed through one of the spaces *f* as before or through one of the gaps *h* and be pulled between the body *a* and tongue *b*. In either case the string end is gripped between the teeth of the tongue and the body. The intact part of the string is then passed round the parcel, then through the second gap *h* into the space *f*, pulled tight in the manner previously described, allowed to retract and become gripped by the second tongue *b* and be afterwards cut off.

A modification of the device is shown in Figs. 6 and 8 in which the hinged tongue member *b* is provided at the opposite side to the hinge with an extension *n* bent to spring over the body *a* to temporarily hold the tongue member in position after the string has been passed through the gap *h*. If required the tongue member *b* may be divided into two parts along the transverse broken line *m*¹ shown in Fig. 6.

The clip shown in Fig. 9 is a modification of that shown in Fig. 3 differing only in respect to gaps *h* through which the string can be pulled and to the fact that the double tongue member *b* is clamped to the wire body *a* by turned-over lugs *o*.

Figs. 9 to 11 show a modification of the clip shown in Fig. 9 in which the body member *a* is made from stamped metal while the double tongue member *b* is riveted at *p* or otherwise secured to it. To facilitate the passage of the string into the spaces *f* as before

described, the tongue member *b* may be turned up slightly at an angle at the corners *q* nearest the gaps *h*. A further feature consists in providing the tongue member with a recessed knife edge at *r* adjacent a recess *s* in the body *a* to enable string to be cut when required.

In some cases, as for instance, with the larger diameters of string or cord, the rigidity of the double tongue members *b* renders it difficult to pass the cord through the gaps *h* into the spaces *f*. I therefore provide, as shown in Figs. 12 and 13 divided members *b* which are made resilient by providing their inner ends with lateral pivots *2* passing freely into holes or slots *3* formed in turned-up plugs *4* in the body member *a*. In conjunction with such pivoted members I employ a flexible plate spring *5* riveted to the body *a* and extending over the rear portions of members *b*. When, therefore, the string or the like is being passed through the gaps *h* into spaces *f*, the members *b* give somewhat against the influence of the spring but nevertheless grip the cord and hold it as previously described.

All the forms of clip previously described have double tongued members *b*. I would, however, have it understood that all such forms may have a single member *b* as in Fig. 14, riveted or otherwise attached to the body member *a* by its rear end, a gap *h* and space *f* being employed as before. In such clip it is necessary to provide means for holding one end of the string. This may be done by tying a knot at one end of the string and passing the other end through a hole *6* in the body member *a*, such other end being passed round the parcel and through the space *f* so that it may be held after tightening up in the manner previously described. This or any of the other forms shown may have a hook or slot for a similar purpose. The single-tongued forms may also be nailed by their plain ends to boxes or picture frames, or be stapeled or otherwise fastened to paper pins, large envelopes or the like, in which connection they perform the functions of a buckle or button.

In all forms of the device, a tube *7* either flattened or rounded, either complete or slotted as shown in Fig. 4 may be employed to give greater security in fastenings made with the help of the present invention. This tube is passed on to the string and slid down over the gripping device and the ends of the string, on which it is adapted to fit tightly.

In all forms of the device some edge thereof may be sharpened so that string may be cut on it, to avoid the use of a knife after a fastening is made by means of the device. This sharp edge may be conveniently made at *g*¹, *g*² in Fig. 4 of the accompanying drawings or as in Fig. 9.

All forms of the device are designed for two opposite tensions. There is no strain on the tongue when the cord used therewith is

put under tension by pulling on the ends thereof. The tongues are in all forms of the device supported under the tension of the cord, when pulled taut and let go, by the fact 5 that they overlap the sides of the corresponding spaces in the frame or body.

Where the devices are used in connection with leather straps, webbing or the like the ends of the clips would be flat instead of 10 curved thus leaving the spaces *f* as very narrow slots.

Whether the tongue members *b* are separately attached to or form part of the body members *a* they are preferably made of tempered steel which is softened at local points 15 where intended to be secured to the body members by lug connections.

What I claim as my invention and desire to secure by Letters Patent is:—

20 1. A device to facilitate tightening and automatically to grip string or cord comprising a body having an open-sided aperture therein and a tongue of resilient material having one end rigidly anchored to said body and its 25 other free end partially covering said aperture.

2. A device to facilitate tightening and automatically to grip string or cord comprising a body having open-sided apertures therein 30 and tongues of resilient material rigidly anchored at one part to said body and having their free ends partially covering said apertures.

3. A device to facilitate tightening and au-

tomatically to grip string or cord comprising 35 a sheet metal base having an open-sided aperture therein and a notched tongue of thin resilient material having one end rigidly anchored to said base and its other notched end free and partially covering said aperture, 40 said notched end being spaced slightly apart from the adjacent curved part of the wall of said aperture.

4. A device to facilitate tightening and automatically to grip string or cord comprising 45 a sheet metal base having open-sided apertures near the ends thereof, and notched tongues of resilient material rigidly anchored to said base and having their notched ends free and partially covering said apertures, 50 said notched ends being spaced slightly apart from the adjacent curved parts of the walls of said apertures.

5. A device according to claim 1 having a 55 knife edge on one side for string cutting purposes and a gap in the body member through which the string can be passed to be cut.

6. A device according to claim 2 having a double-tongued gripping member co-operating with two gapped apertures in the body, 60 said gripping members having the corners nearest to the gaps turned up at a slight angle to facilitate the passage of the string or cord into the gapped apertures in the body member.

In testimony whereof I have hereunto set my hand.

HUGO JOHN BUCHANAN-WOLLASTON.
